UNITED STATES PATENT OFFICE.

FRANK BYCROFT KEALL AND WILFRID THOMAS MINETT, OF LEICESTER, ENGLAND,
ASSIGNORS TO UNITED SHOE MACHINERY CORPORATION, OF PATERSON, NEW JER-
SEY, A CORPORATION OF NEW JERSEY.

LEVELING MACHINE.

Application filed May 15, 1922. Serial No. 561,201.

To all whom it may concern:

Be it known that we, FRANK B. KEALL and WILFRID T. MINETT, subjects of the King of England, and residing at Leicester, 5 Leicestershire, England, have invented certain Improvements in Leveling Machines, of which the following description, in connection with the accompanying drawings, is a specification, like reference characters on the 10 drawings indicating like parts in the several figures.

This invention relates to the supporting of boots or shoes (hereinafter referred to generically as "shoes") during the operation 15 of leveling the sole and is concerned exclusively with providing for leveling the sole of a shoe by a shaped bottom-pressing form while the shoe is on the last as distinguished from the customary practice of leveling 20 shoes by such a form while there is no last in the shoe but a mere metal foot forming part of the machine.

In making a welt shoe it is desirable to 25 avoid withdrawing the last from the shoe until as late a stage in manufacture as possible and consequently leveling machines are in common use for this class of work in which the shoe, on the last, is jacked and operated on by means which in some measure accommodates itself to the last bottom. The limits of strength met with in lasts and in jacks for lasts and the uncertainty of attaining a definite position of the shoe bottom with shoes supported by jacks have imposed serious limits on the pressure which 35 such a machine could be arranged to apply and the development has proceeded along the line of pressures locally applied over small areas and moving from place to place.

40 Thus the total pressure applied is not beyond the strength of the last or the machine, and the maximum pressure per unit area may be kept at the point desired. Such machines (which are generally of the roller type) have, for some kinds and conditions 45 of work, the disadvantages that the leveling does not occur between the last bottom and a replica of it, since a leveling roll is not the equivalent of a replica of the last bottom, and further, the shoe cannot, as a whole, be kept under pressure long enough to treat 50 each part of it thoroughly without embarrassing slowness of operation. Consequently in addition to the leveling operation

involving the steps of jacking and unjacking, under certain conditions after-treatment has commonly been required to touch up the bottom of the shoe to supplement the action of the machine. 55

In making a McKay-sewn or screwed or nailed shoe the last is withdrawn for the performance of various bottoming operations preceding the sole leveling and consequently advantage may be taken of this fact to support the shoe internally by a massive support or iron foot when leveling so as to permit heavy and relatively long-continued pressure over a considerable part of the shoe bottom at once without, however, unduly slowing up the leveling, and this has led to the general use for such work of so-called direct pressure levelers in which the leveling occurs between a metallic foot inserted in the shoe and a mold or form of the shape desired for the shoe bottom. While this system permits the use of heavy pressures the leveling is still performed between parts one only of which is a reproduction of the shape desired, since the metallic foot necessarily falls much short of being a full reproduction 70 of the last. On the other hand, the distortion to which this class of work is subject as the result of the withdrawal of the last preparatory to the bottoming operations 75 and, particularly, of the special bottom-attaching operations themselves, necessitates the high pressures which this class of machine permits and renders unsuitable the only type of leveling machine known prior to the present invention which can perform 80 leveling directly on the last, namely that first above discussed. 85

In view of the foregoing, an important object of this invention is to provide for effecting the leveling operation upon the wooden last in a machine of the direct pressure type such as, for example, is described in said 95 patents, or any other direct pressure leveling machine. This will allow the use for any class of shoe of an adequate pressure, owing to the type of machine used, a proper application of the pressure at all parts, owing to the leveling being performed between the last bottom and a form which is the replica 100 of it, and the application of the pressure for a considerable time, without disadvantageously prolonging the leveling operation, 105 since the pressure is applied over a consider-

able area of the shoe bottom at once instead of being limited to a small area and carried progressively over the shoe.

Another object of the invention is to provide an improved organization constructed and arranged so that the operator may readily place a shoe (on a last) in operative relation to the bottom treating means of a leveling machine and so that, without the necessity of his performing any other act than the placing of the shoe in the supporting means, the shoe will be correctly positioned and supported during the leveling operation.

To the accomplishment of these objects the invention comprises as one feature, in or for a leveling machine for leveling the bottom of a shoe while on a last by the action of a shaped bottom-pressing form, the provision of a cradle wherein the shoe rests during the leveling thereof.

Having regard to the variety of forms which a cradle for this purpose may take, as instanced by the examples hereinafter described in detail, it may be here convenient to state certain properties at least one of which a work support must possess to constitute it a cradle as herein understood. These properties are:—

(a) That the last when placed in the support is forthwith firmly held thereby against leveling pressure without calling for clamping or adjustment, given that the proper work support for the size or style of last is present in the machine or that the proper adjustment of an adjustable work support has previously been made.

(b) That the work is located or steadied by the work support exclusively by contacts with the external surfaces of the last (or with the shoe upper on said surfaces) as distinct from the location or steadyng of the last by engagement of a member in its last-pin hole.

(c) That the work support includes a fore-part rest having an extensive area of contact with the top of the last not only in the bottom of the hollow behind the toe and forward of this location but also rearward of this location, which whole area has been carefully molded substantially to the precise shape of this portion of the shape of last to be dealt with;

(d) That a last pin is not depended upon for locating the last for the operation; and

(e) That the last is steadied for the leveling without heavy strains being put upon a last-pin.

A further feature of the invention consists in the provision in a machine for leveling the bottom of a shoe by the action of a shaped bottom-pressing form, of a work support adapted to sustain in proper position against the leveling pressure a shoe upper on a last and comprising correlated means

to effect adjustments of the support so as respectively to maintain substantially unvaried one or both of (a) the relative aspect of approximate parallelism of the shoe bottom and form, and (b) the relative longitudinal position of the shoe as a whole and of the form, with changing sizes of shoes.

The invention is herein illustratively set forth as embodied in a direct pressure leveling machine of the type shown and described in United States Letters Patent No. 1,859,507, granted Nov. 23, 1920, on application of Jerram and Gouldbourn.

The above and other objects and features of the invention will become fully evident to those skilled in the art from the following description, given by way of example, of a preferred embodiment of the invention.

In the drawings:—

Figure 1 is a side elevation of one form of a shoe support according to the invention;

Figure 2 is a sectional elevation on the line 2—2 of Fig. 1;

Figure 3 is a sectional elevation on the line 3—3 of Fig. 1.

In the construction illustrated, the outer end of the foot-carrying cylindrical shank 11 of the leveling machine described in the cited patents is modified to have or to receive at its outer end a supporting face or foot 12, substantially at right angles to the axis of the shank, on which face is fixed a cast-metal cradle 13 to support the shoe B in opposed position to the shaped pressure-form A. The face may be either formed on the top of a block clamped by any convenient means to the shank 11 or may be formed on a block or supporting member 14 integral with the shank 11 according as it is deemed likely that supporting feet may be required to be used interchangeably with the cradle, and the mass of interchangeable parts is therefore sought to be reduced. The cradle is fixed to the face by two bolts 15 pivoted in recesses 16 formed in the supporting member 14 on pins 17 parallel to and below the face 12 and held by the recesses against movement on their pivots lengthwise of the shoe. The bolts 15 have at their outer ends nuts 18 and washers 19 which engage over slotted lugs formed on the cradle, and thereby determine the longitudinal position of the cradle relatively to the form. By slackening the nuts and swinging the bolts about their pivots the cradle is quickly released. The cradle is positioned transversely on the face by a tongue 20 on the cradle which enters a groove formed in the face 12 longitudinally of the shoe.

The cradle is open at the top and is lined with a comparatively thin and unyielding layer 21 of felt or other resilient material (say of a quarter of an inch thickness) the purpose of this lining being not so much to afford accommodation to the last and shoe B

as to secure a frictional grip on the leather without damage thereto. The actual positioning of the shoe is due almost exclusively to the form of the metal cradle which is shaped internally to conform closely to the shape of the top of the last which it is to support. At the forepart the cradle is closed at its underside and is intended to engage substantially the whole of the top of the last but towards the heel end an opening is formed to allow the cone of the last to project downwardly. The side walls of the cradle, however, may extend continuously all around the shoe, and will in any event 10 preferably embrace the lateral and terminal portions of the heel, so that there is unbroken support along a longitudinal band on the surface of the last from one side to the other of the last around the heel end in continuation of the support afforded by the complete cradle at the forepart.

The cone of the last is supported on the tabular top of a post 22 which is adjustably mounted in a rectilinear guideway 23 formed on the block 14 aforementioned. Any jack pin is preferably omitted. The guideway 23 extends in a direction lengthwise of a shoe on the cradle 13 and is inclined upwardly towards the toe end of the cradle so that when a cradle is fixed on the block 14 and the post 22 moved along the guideway 23 according to the size of the cradle the post will be raised or lowered, thereby maintaining contact between it and the cone of the last which, with changing sizes, comes at different heights from the block 14 as well as at different positions along it. The post 22 may conveniently have pivotally connected to it one end of a link 24 the other end of which has projecting through it a pin 25 the ends of which may be received in aligned slots or grooves 26 formed in the face 27 of the cradle 13 and acting as bearings for the pin ends. The position of the slots 26 in the face 27 varies according to the size of the cradle, and when a cradle is changed for one of a different size the pin 25 in the link 24 is placed in engagement with the slots 26 in the cradle 45 as the cradle is placed in position and the post 22 is thereby correctly positioned along the inclined guideway 23 according to the size of the cradle. The operator is therefore relieved from the necessity of attention 50 to the position of the post which is determined entirely by the angular disposition of the guideway and the definite and correlated position of the slots in the various cradles.

60 Each cradle is shaped to the particular style of shoe which it is to support and it is found that each cradle will efficiently support shoe of two sizes of the same style, the cradle being shaped to fit closely the 65 larger of the two sizes. For example, in a

run of shoes of the same style and of sizes from six to eleven, three cradles would be required, one for sizes six and seven, one for eights and nines, and one for tens and elevens.

70 The present invention thus provides for the leveling of welted work better and more completely in the one operation than is possible with the practice heretofore used and the consequent avoidance of much of the 75 after-treatment customary under it.

Again, the invention provides for the employment of a single type of machine for classes of work (that is welted and McKay work) for which different types of machines have been necessarily employed heretofore.

Having described our invention, what we claim as new and desire to secure by Letters Patent of the United States is:—

1. In a leveling machine for leveling the bottom of a shoe while on a last by the use of a shaped bottom-pressing form, a cradle formed in accordance with the external surface of the portions of the last received by the cradle wherein the shoe rests during the leveling thereof, and means for applying pressure between the form and the cradle.

2. In a machine for leveling the bottom of a shoe by pressure delivered by a shaped bottom-pressing form, a work support adapted to sustain a shoe upon a last in proper position against the leveling pressure, and comprising correlated means for effecting adjustments of the support so as respectively to maintain substantially unvaried the relative aspect of the shoe bottom and form.

3. In a machine for leveling the bottom of a shoe, a shaped bottom-pressing form, and a work support adapted to sustain a shoe upon a last in proper position against the leveling pressure and comprising correlated means for effecting adjustments of the support so as respectively to maintain substantially unvaried the relative longitudinal position of the shoe as a whole and the form with changing sizes of shoes.

4. In a machine for leveling the bottom of a shoe, a shaped bottom pressing form, a work support having generally the contour of the upper front part of the last, and a block for supporting the cone of the last.

5. In a machine for leveling the bottom of a shoe, a shaped bottom pressing form, a work support having generally the contour of the upper front part of the last, and a block for supporting the cone of the last, the block being adjustable longitudinally of the shoe.

6. In a machine for leveling the bottom of a shoe, a shaped bottom pressing form, a work support having generally the contour of the upper front part of the last, and a block for supporting the cone of the

last, the block being adjustable longitudinally and vertically of the shoe to place its cone contacting surface at the proper height for lasts of different sizes..

5. 7. In a machine for leveling the bottom of a shoe, a shaped bottom pressing form, a work support having generally the contour of the upper front part of the last, and a block for supporting the cone of the last, 10 and a sloping guidway along which the block is adjustable to fit different sized lasts.

8. In a machine for leveling the bottom of a shoe, a shaped bottom pressing form, 15 a work support having generally the contour of the upper front part and the lateral

heel portion of the last, and a block for supporting the cone of the last.

9. In a machine for leveling the bottom of a shoe, a shaped bottom pressing form, 20 a work support contacting with the upper toe-ball-instep portion and with the lateral and terminal heel portions of the last and substantially fitting them, and a member contacting with the upper surface of the 25 last-cone and constructed and arranged to support it without the use of a jack-pin.

In testimony whereof we have signed our names to this specification.

FRANK BYCROFT KEALL.
WILFRID THOMAS MINETT.
